BEE-SHAPED SEAT FOR PLAYGROUND APPARATUS

Robert S. Wormser, Hillsdale, Mich., assignor to Game Time, Inc., Litchfield, Mich.

Filed Oct. 27, 1972, Ser. No. 301,621

Term of patent 14 years

Int. Cl. D21—02

U.S. Cl. D34—15 B

FIG. 1

FIG. 2

FIG. 4

FIG. 3

FIG. 1 is a side, elevational view of a bee-shaped seat for playground apparatus in accord with my new design, the opposite side being identical thereto,

FIG. 2 is a front, elevational view of the design,

FIG. 3 is a top, plan view, and

FIG. 4 is a rear, elevational view.

I claim:

The ornamental design for a bee-shaped seat for playground apparatus, substantially as shown and described.
